OUTDOORS COIN DEPOSITORY

David L. Shain, Harrisburg, Ill.

Application May 2, 1952, Serial No. 285,631

2 Claims. (Cl. 232—43.1)

1

The present invention relates to ways and means suitably and satisfactorily designed to expedite the collection of coins for payment of services wherein the collectors are duly appointed representatives of newspaper offices, dairies, icemen, grocerymen, and so on.

It is a great convenience to residential patrons and customers as well as to newspaper carriers, milk delivery men, and others to systematize delivering articles, and at the same time picking up the pay therefor. Assuming, for example, that the newspaper delivery boy calls and presents his bill for payment for services rendered, the housewife may not have the correct change or may be absent from home at the time. Or, it may turn out that the boy, in attempting to make his collection, may have to return time and again because of this unfortunate inability to time his calls with home and other requirements of his customers. All of this is, of course, well known and milk delivery men and others have the same difficulties. While it is true that others have offered ways and means to alleviate the mutual difficulties of those involved, the fact that out-of-doors coin pickup depositories have not come into widespread adoption and use indicates that a depository of proper construction has not as yet made the grade. It is therefore the object of the instant invention to provide a simple, practical, safe and economical device in which manufacturers, users and others will find their respective manufacturing requirements and general needs fully met and properly presented.

With a view toward meeting the expected requirements of the trade and bettering the accomplishments of others engaged in the same line of endeavor, the instant matter has to do with an out-doors depository which is characterized primarily by a receiver which has window means so that the collector may, at a glance, determine whether the coins to be picked up are contained in the receiver.

Another improvement has to do with a window-equipped coin receiver and pickup device which is also provided with conveniently usable indicators or signs which may be brought into use and which may be seen from the sidewalk or street to further aid in taking care of the mutual requirements of the parties involved.

More specifically, the invention appertains to a suitably shaped, window-equipped casing which provides a receiving chamber and which has conveniently arranged coin intake slots and has at least one coin discharge slot through

2

which the coins which are to be picked up gravitate. A simple spring member is arranged in the receiver and cooperates with the discharge slot and provides a closure and said member is operable by a key which is inserted by the authorized user of the depository.

A further feature of construction has to do with means constructed as stated wherein a simple slotted barrel is rotatably mounted in the receiver at a convenient point and which serves to accommodate the insertable key from either side, making it possible for the duly authorized coin collector to insert the key from either the right or left side of the depository.

Other objects, features and advantages will become more readily apparent from the following description and the accompanying sheet of illustrative drawings.

In the drawings:

Figure 1 is a view in section and elevation showing the outdoors type depository and the manner in which it is constructed and mounted for use.

Figure 2 is an elevational view of the same, observing it in a direction from right to left.

Figure 3 is a cross-section on the horizontal line 3—3 of Figure 2, looking in the direction of the arrows.

Figure 4 is a cross-section on the line 4—4 of Figure 2.

Figure 5 is a perspective view of the aforementioned key-accommodating barrel.

Figure 6 is a perspective view of the key which is used by the newspaper carrier or boy or other authorized representative.

Briefly, the over-all construction may be conveniently designated, and properly so, as an out-of-doors type depository in which the customer or other residential patron places a prescribed amount of money, usually in coins. In addition, however, the device is a sort of signal in that it includes selectively usable indicators or signs.

The principal part which may be called the casing or depository is denoted by the numeral 8. It may be of any hollow, box-like form and of any appropriate configuration. It is here shown as approximately semi-circular in form and it is characterized by a vertical back wall 10, a curvate front wall 12, and spaced parallel flat side walls 14—14. The upper half portion of the front wall 12 is solid and the lower half portion is provided with a channel-shaped frame 16 for a glass or equivalent transparent panel 18 which latter provides the aforementioned

window. The window permits convenient inspection of the chamber or receiving space 20 to be made for the convenience of all concerned. The curvate window forms a sort of chute for the coins 22 which, as shown in Figure 1, are adapted to be discharged or dispensed by way of the discharge slot 24 at the bottom of the depository. Suitable coin drop-in slots 26 are provided in the sides. Additional shorter slots 28 are also provided and these radiate from circular openings which are provided in the walls 14 and serve as bearings for the flanged end portions 30 of the rotary or turnable barrel 32. The flanged ends extend through the bearing holes and the barrel has diametrically opposite, selectively usable slots 34 and 36 at opposite ends. These slots are adapted to register with the slots 28. They are also adapted to accommodate the actuating finger 38 on the shank portion 40 of the crank-shaped key 42. In practice, the newspaper carrier boy, milk delivery man, or other authorized representative and collector will be provided, of course, with a key of the type shown. This is the sort of key which is susceptible of being placed in through the slots 28 in the right or left sides of the depository, as is obvious. To do this, it is necessary to line up one of the slots 34 or 36 with the selected slot 28. This allows the member 32 to be passed through the slot 28, after which the key now fitting in the barrel can be rotated to place the finger 38 in the dotted line position shown in Figure 1. When in this position, said finger exerts pressure against a flat closure-forming leaf spring 44. The latter is riveted on the interior of the depository, as at 46, at the top. It reaches down and normally bridges and closes off the discharge opening 24. Obviously, however, when the key is turned in the proper manner, pressure of the finger 38 exerted against the spring serves to flex and force the same to the dotted line position shown in Figure 2, whereupon the discharge opening 24 is opened up and the coins drop out into the hand of the collector.

To enlarge upon the over-all efficiency of the device, it is desirable to have certain optionally usable indicators or signs incorporated. To this end, the end portions of the aforementioned back plate 18 project above and below the depository. Then there is a complementary strip or plate 48 provided, and this parallels the plate 18 in spaced relation so that the two, when secured together by the fasteners 50 and 52, form a sort of sheath for the pivoted indicators. Therefore such indicators are conveniently denoted in Figure 2 by the numerals 53, 54, 55 and 56. Each indicator is nothing more than a simple flat plate of metal which has a stop flange 57 along one edge. The inner ends overlap and they are secured by the aforementioned fastenings 50 and 52, as is obvious. These flap-like indicators can be swung into folded, out-of-the-way positions, as shown by the arrows in Figure 2. It follows that if the coins placed in the depository are to be picked up, say, by the newspaper boy, the signalling members 54 or 55 may be swung out to notify the boy accordingly. Or if milk is to be delivered or coins to be picked up for past service, then the milk indicator 53 is brought into play.

It will be understood that the important thing is to provide a suitable and handy depository with slots to feed the coins into the receiver or chamber and slot means to enable the coins to be discharged. It is desirable, too, that the coins should gravitate easily, and therefore the use of

the window as a sort of chute coacting with the slot 24 is important. The simple use of a flat spring to serve as a key-actuated closure or cover for the discharge opening is important. The key-operating barrel for right and left handed use is significant, and the use of the projectable and retractable indicators with suitable printed indicia contribute to the over-all merit of the device.

10 In view of the foregoing description taken in conjunction with the accompanying drawings, it is believed that a clear understanding of the device will be quite apparent to those skilled in this art. A more detailed description is accordingly deemed unnecessary.

15 Minor changes in shape, size, materials and arrangement of parts may be resorted to in actual practice without departing from the spirit and scope of the invention as claimed.

20 Having described the invention, what is claimed as new is:

1. A coin depository for out-of-doors use and to aid authorized collectors in conveniently collecting one or more coins in payment for services rendered comprising a casing adapted to be fixedly mounted on a fixed support, said casing having vertical back, front, and side walls joined with each other in casing-forming relationship, said side walls having coin intake slots, said front 25 wall being arcuate, embodying a correspondingly arcuate window and constituting the bottom portion of a coin delivery chute and having a coin discharge slot at its lower end in close proximity to said back wall, a leaf spring wholly confined in said casing and situated between the side walls and having its upper end anchored on said back wall and its opposite lower end free and biased away from said back wall, terminating in close proximity to one longitudinal side of the discharge slot and cooperating with adjacent portions of the side walls in normally blocking and thus closing the discharge slot, and a key-accommodating barrel in said casing mounted for rotation between said side walls, the intermediate 30 portion of said spring being situated between said barrel and back wall, one end of said barrel being open, opening through the adjacent side wall and being thus accessible for inserting and removing a barrel turning key, said adjacent side wall having opening means communicating with the cooperating open end of said barrel, said barrel having at least one lengthwise slot communicating with the adjacent open end of said barrel and which may be turned to a position, by turning 35 said barrel, to be bridged by a cooperating intermediate portion of said spring, whereby to permit a key having a laterally projecting finger to be inserted through the opening means and the adjacent open end of the barrel in a manner to 40 allow the finger to project through the slot in the barrel and into engagement with the intermediate portion of said spring so that when the key and barrel are simultaneously rotated, flexing pressure will be exerted against the spring in 45 a manner to move said free end of the spring toward the back wall and to swing said free end to a position uncovering said discharge slot.

2. A coin depository for out-of-doors use and to aid authorized collectors in conveniently collecting one or more coins in payment for services rendered comprising a casing adapted to be fixedly mounted on a relatively stationary support, said casing embodying a flat vertical back wall, spaced parallel vertical side walls at right angles 50 to said back wall, and an arcute front wall op-

posed to said back wall and joined with said back wall and side walls, said front wall having a coin discharge slot adjacent the lower end of said front wall and in close proximity to the lower end portion of said back wall, the arcuate lower portion of said front wall cooperating with the adjacent portion of said side walls in defining the coin gravitating chute leading to said coin discharge slot, a leaf spring of a width approximately equal to the space between said side walls, said leaf spring being fully confined within the space of said casing, the upper end of said spring being fixed to said upper end portion of said back wall, the lower end of said spring being free and sprung away from the corresponding lower end portion of said rear wall and terminating adjacent the lower end portion of said front wall and being positioned on one longitudinal side of the discharge slot remote from the back wall and thus blocking and closing said coin discharge slot, said side walls having coin intake slots, said side walls being further provided with aligned key-hole shaped openings therein, a horizontally disposed barrel arranged in the space of said casing and bridging said space in spaced parallelism in respect to the intermediate portion of the back wall and having flanged end portions journaled for rotation in the respective key-hole shaped openings, said barrel being open at one end to receive a key and having at least one end-wise key insertion slot opening through said flanged open end and communicable with one of said key-hole shaped openings, said spring being

located between the barrel and back wall, the intermediate portion thereof being adapted to bridge the slot in said barrel when the slot is turned to a position for cooperation with said spring, whereby to permit a key with a laterally projecting finger to be inserted through the selected key-hole shaped opening and to be inserted into the barrel by way of the open end of the barrel and bore of the barrel and to thus allow the finger on the key to be projected through the slot in the barrel and to be brought into engagement with said spring so that when they key and barrel are simultaneously rotated, flexing pressure will be exerted against the spring by way of the finger in a manner to move the free end of the spring toward the back wall, to swing said free end to a position wherein the discharge slot is no longer blocked and is therefore uncovered to permit coins to be discharged therethrough without interference from said free end.
